COLLAPSIBLE BACKREST
J. Paul Fortier, U.S. Rte. 1, Foxboro, Mass.
Filed June 4, 1963, Ser. No. 285,283
10 Claims. (Cl. 297—351)

This invention relates to backrests and more particularly to a collapsible backrest having capacity for readily and selectively erecting in support position and collapsing into a conveniently small, storage and hand portable bundle.

Many vacationers and sporting enthusiasts forego the convenience and enjoyment of chairs and backrests at beaches and other recreation areas because of the difficulty of storing and transporting them to and from the beach or other place of use. Even the few such chairs and backrests which have been made collapsible to reduce storage space required and to make them more portable, nevertheless are generally still too bulky, cumbersome or heavy for easy portability, or for the average individual provide too difficult and tedious a chore for their assembly and disassembly at the point of use.

These problems are overcome by the present invention of a collapsible backrest which also incorporates other desirable features and advantages. Among these other desirable features and advantages are the provision of a collapsible backrest which requires only a relatively small number of parts. Another desirable feature is the provision of a collapsible backrest which provides a particularly comfortable support to the user's back in that only a flexible membrane such as a plastic or fabric with its inherent shape conforming characteristics makes contact with the back of the user. Other desirable features include extreme simplicity of operation with very few manipulations required in erecting the backrest to support position and collapsing the backrest for ready storage and portability. Also, it may be compacted to the form of a small convenient bundle for storing or carrying with the hard metal components being encased in the relatively soft membrane which provides a protective padding and thereby minimizes possibility of discomfort or injury to an individual carrying the bundle. Further advantages include that of a very rugged backrest, yet one which is comprised of very simple and inexpensive components.

A primary object of the present invention is the provision of a collapsible backrest with capacity for readily compacting into a conveniently small, hand portable bundle.

Another object is the provision of a collapsible backrest wherein only flexible membrane makes support contact with the body of the user.

A further object is the provision of a collapsible backrest which in the compacted, hand portable bundle form inherently has its hard metal components enveloped in comparatively soft, protective membrane wrapping.

And another object of the provision of a collapsible backrest which requires no tools of any kind and is relatively easy to erect into support portion and to collapse into a compact, hand portable bundle.

Other objects include the provision of a collapsible backrest which is rugged, relatively simple in construction, inexpensive to manufacture, and reliable in its operation.

These and other objects, features and advantages are achieved generally by the provision of a pair of channel members, each pivotally carrying telescoping rods in the trough of the respective channel, a flexible membrane carried by the telescoping members, and a foldable cross bracing structure fixed to the channels for holding the channels in support position when the backrest is erected for use.

By making the flexible membrane with overlapping

2

portions at its sides to form loops or elongated tubular formations circumscribing the telescoping rods, a simple and rugged back support arrangement of the membrane by the telescoping rods, as well as suitable capacity for compacting in folded form is thereby achieved.

By providing a flexible strap attached at one end to the top of the membrane at substantially the fold thereof when in collapsed position, and providing fastening means at spaced intervals on the strap, a suitable locking arrangement for holding the structure in a compacted, hand portable bundle is thereby achieved, as well as an arrangement which prevents the locking strap from dragging in the dirt and sand when the backrest is in erected support position.

By making the cross bracing structure in the form of a spacer bar of two sections pivotally fixed to each other at one of their ends, and to the respective channels at the other of their ends, and an angularly disposed rigidizing member for each of the sections pivotally mounted on the respective section and the associated channel, a rugged and simple cross bracing structure, as well as one having inherent ease in erecting and collapsing to compact the structure is thereby achieved.

By providing a slot in each of the channels with an offset notch in the upper end of each channel for guiding and locking a pin in the corresponding end of the angular rigidizing members, a simple and effective operating arrangement for the support structure is thereby achieved.

By providing openings at spaced intervals along one leg of each channel and providing an arm pivotally mounted at one end to the corresponding telescoping rod and constructed at the other end to engage a selected opening, a simple and effective arrangement for varying the angle of support of the backrest is thereby achieved.

By providing a flexible chord or strap fixed at each of its ends to the bottom ends of the channels, an effective arrangement for both providing a suitable carrying handle for the backrest in compacted bundle form, along with a simple arrangement for retaining the upper end of the membrane in taut condition for improved comfort and support action of the overall backrest is thereby achieved.

These and other features, objects, and advantages of the invention will be better understood from the following description taken in connection with the accompanying drawings of preferred embodiments of the invention and wherein:

FIG. 1 is an elevation showing the invention in a collapsed condition forming a compact bundle for ready hand portability or storage;

FIG. 2 is a view of the FIG. 1 embodiment shown partially unfolded as a first step in its erection as a backrest and a next to the last step in compacting into a hand portable bundle;

FIG. 3 is a view of the unfolded back of the FIG. 1 embodiment illustrating a further unfolding stage in its erection as a backrest;

FIG. 4 is a view of a portion of a channel illustrated in FIG. 3 to more clearly show construction;

FIG. 5 is an illustration of an alternative construction of a portion of the cross bracing arrangement illustrated in FIG. 3;

FIG. 6 is a side elevation showing the completely erected backrest in support or use position;

FIG. 7 is an enlarged scale side elevation of one of the channel members of the present invention with some of the associated structures folded therein with some components only partially shown;

FIG. 8 is a cross section taken on line 8—8 of FIG. 7;

FIG. 9 is an end view of FIG. 8;

FIG. 10 is a back view of a portion of the channel member shown in FIG. 7.

Referring to the drawings in more detail, a collapsible backrest made in accordance with the present invention is designated generally by the numeral 12. The collapsible backrest 12 has a pair of channel members 14 and 16, preferably of such strong, rigid material as aluminum alloy or steel, both being of substantially similar construction. Thus, while only the channel member 14 and its associated foldable assembly is shown in detail in FIGS. 7 through 10, it should be understood that such description also applies to the channel 16 and its associated foldable assembly.

Channel member 14 has a cross sectional shape in the form of a trough shown in FIG. 9 with a back or bottom closure 18 and substantially parallel sides or legs 20 and 22. One end of the channel member 14 has mounted thereto, by pivot pins 24 and 26 (FIG. 8), a ground support channel member 28. The ground support channel member 28 has a cross sectional configuration to fit the trough of the channel 14 and a pivotal capability of swinging outwardly from the trough of the channel member 14 so that its sides or legs enter respective slots 30 and 32 (FIG. 10) in the back side 18 of the channel member 14 until the upper surfaces of the sides of the ground support channel member 28 engage the ends 34 and 36 of the slots 30 and 32 respectively so as to act as stops for the ground support channel member 28. In this swung out position, the ground support channel member 28 (FIG. 6) provides an area of contact 38 with the surface of the terrain 40, which is usually soft sea sand, and thereby prevents the end of channel member 14 from sinking into the terrain 40 when under load. In the event that the backrest 12 is to be used only on hard surfaces, the ground support channel 28 may be eliminated entirely or replaced by a small fixed pad at the end of the channel member 14 (not shown).

A flexible cord or strap 42 is also fixed to the end of the channel members 14 and 16 carrying the pivot pins 24 and 26, as by a snap fastener 44 at one end of the strap 42 and an enlarged head rivet 46 (FIGS. 2, 3) at the other end of the strap 42. Thereby, the strap 42 provides a suitable handle which enhances hand portability of the collapsible backrest 12 when in the collapsed and compacted package form shown in FIG. 1. The strap 42 also provides a highly desirable limiter to extent of sideward separation of the lower ends of the channel members 14 and 16 when the collapsible backrest 12 is in the erected support position shown in FIG. 6 as will be hereinafter further described.

The backs of the channel members 14 and 16 also carry slots 48 and 50 for slidably guiding follower pins 52 and 54 in one end of angularly disposed rigidizing braces 56 and 58 respectively. The rigidizing braces 56 and 58 have pivot pins 60 and 62 at their other ends providing pivotal mounting to each of spacer bar sections 64 and 68 respectively at positions distal from pivot pins 70 and 72. The pivot pins 70 and 72 provide pivotal mounting for one of the ends of each of spacer bar sections 64 and 68 to the backs of the channel members 14 and 16 respectively. The other end of each of the spacer bar sections 64 and 68 are pivotally coupled together by a pivot pin 74.

Each of the slots 48 and 50 at their upper extremities carry an offset locking opening such as shown at 76 in FIG. 4 in position such that when the channel members 14 and 16 are pulled outwardly away from each other to the positions shown in FIG. 3 from the collapsed position shown in FIG. 2, the follower pins 52 and 54 will ride up slots 48 and 50 respectively and become engaged and locked in the offset locking opening 76. Also, the spacer bar section 60, adjacent the pivot pin 74, has a stop recess 77 arranged to engage a cooperating stop pin or boss 78 (FIG. 3) on the spacer bar section 64. Thereby, as the pivot pin 74 moves upwardly from the position shown in FIG. 2 to the open position shown in FIG. 3, such upward movement will come to a halt and further movement beyond the fully extended position of the spacer bar mem-

bers 64 and 68 shown in FIG. 3 will be prevented by the engagement of the stop recess 77 and the boss 78. The components are dimensioned to provide that the follower pins 52 and 54 will become locked in the locking recesses 76 when the boss or stop pin 78 firmly engages the stop recess 77, thereby providing a rigid, self locking and self-retaining framework. The rigidity and self locking aspect of this framework is further enhanced by dimensioning the flexible strap or cord 42 to be pulled taut when the follower pins 52 and 54 fall into the locking offset openings 76. In some instances, to further increase the tightness of the cord 42, it may be desirable to release the snap fastener 44 end of the cord 42 during the opening operation until the channels 14 and 16 have been laterally separated and the follower pins 52 and 54 lock in place in the locking offset openings 76. Thereupon the cord 42 may then be manually pulled tight and fastened in place by the snap fastener 44.

An alternative construction for rigidizing braces 56 and 58 is shown in FIG. 5 where in place of a single member rigidizing brace as 58, two sections 80 and 82 are pivotally mounted together by pivot pin 84 and a boss and stop arrangement 86 which may be such as described in connection with the boss 78 and stop recess 77. Further locking in place in the erected support position may also be provided by a hole and boss arrangement 88 in the rigidizing brace sections 80 and 82 respectively. In this alternative construction, pivot pin 89 does not move in a slot and is rather fixed in position in the back side of the channel 16. When it is desired to fold the assembly to the position shown in FIG. 2, pressure is brought to bear behind the pivot pin 84 so as to push in the direction away from the pivot pin 72 to thereby cause the spacer bar section 68 and rigidizing brace sections 80 and 82 to fold downwardly over the channel 16 in somewhat similar manner to the folding shown in FIG. 2.

Referring again to FIG. 8, in the folded position, the channel member 14 carries in its trough the ground support channel member 28 and a pair of cylindrical telescoping rods comprised of an outer and an inner telescoping rods 90 and 92 respectively. The outer telescoping rod 90 has pivot pins 94 and 96 fastened to its upper end as by brazing, welding or other suitable means. The pivot pins 94 and 96 are pivotally carried in holes in the sides 20 and 22 respectively of the channel member 14. Spacer washers 98 and 100 may be provided to prevent undesired sideward movement in the trough of the channel member 14. The bottom end of the outer telescoping rod 90 may carry a closure plug 102 to prevent access of sand and dirt therein.

The inner telescoping rod 92 may have a stop button 104 protruding through a side wall opening in the inner telescoping rod 92 and carried by a spring 106 anchored by a plug 108 in the hollow of the inner telescoping rod 92. The upper end of the inner telescoping rod 92 may also have a closure plug 110 to prevent sand and other foreign matter from entering internally thereof. It also provides a place for gripping with the fingers for extending the inner telescoping rod 92 until the stop button 104 engages the top rim 112 of the outer telescoping rod 90 as shown in FIG. 6 to thereby increase the effective support length 114 of the collapsible backrest 12.

When the telescoping rods 90 and 92 are in the shortened position shown in FIG. 8, the pressure of the plunger or stop button 104 from the spring 106 will, because of friction against the inside surface of the outer telescoping rod 90, tend to hold the inner telescoping rod 92 in place. Also, as explained above, the channel member 16 carries a similar outer telescoping rod 116 and an inner telescoping rod 115 with a similar spring pressed stop button 117 (FIG. 3). The outer telescoping rod 116 is similarly mounted to the end of channel 16 by pivot pins 117.

The outer telescoping rod 90 also carries a pivot pin 119 rigidly fixed to its outer wall as by brazing, welding

or other suitable means. The pivot pin 119 provides a fulcrum and mounting arrangement for one end of a backrest angle adjusting arm 118 having a projection 120 at its other end. The projection 120 has a configuration which fits selectively into any one of a plurality of backrest angle adjusting holes 122, 124, 126 and 128 in the side 22 of the channel 18, thereby permitting a selective adjustment of the angle of inclination 130 of the collapsible backrest 12. It will be noted that by making a relatively close fit at the pivot pin 119, the inherent lateral spring action of the angle adjusting arm 118 will continuously exert an outward pressure against the side 22 of the channel member 14 so as to continuously retain the projection 120 in any selected angle adjusting hole 122, 124, 126 or 128.

A similar angle adjusting arm 130 with similar projection 132 (FIG. 3) is provided on the outer telescoping rod 116 to engage similar angle adjusting holes in the side of the channel 16 (not shown).

A thin flexible membrane 134 of a suitable plastic or woven fabric such as canvas has overlapped sides fastened as by stitching 136 or other suitable fastening means to form lower elongated tubular formations 138 and 140 and, aligned therewith, upper elongated tubular formations 142 and 144 respectively along the sides of the flexible membrane 134. Openings 146 and 148 are provided between the aligned, elongated lower and upper tubular formations and are preferably reinforced as by a binding 149 at the edges of the membrane 134 to provide additional strength and wear qualities.

The upper ends of the upper elongated tubular formations 142 and 144 are closed or sealed as by stitching 150. Fitted inside of the lower elongated tubular formations 138 and 140 are the telescoping rods 92 and 116 respectively, which by means of the pivot pins 119 protruding through the membrane 134 tend to hold it in place on the telescoping rods.

The inner telescoping rods 92 and 115, because of the openings 146 and 148, may be inserted into the upper elongated tubular formations 142 and 144 respectively as shown in FIGS. 3 and 6, or removed therefrom at the pleasure of the user. Thus, the inner telescoping rods 92 and 115 will be inserted in the upper elongated tubular formations 142 and 144 to increase the support length 114 as shown in FIG. 6 when the collapsible backrest 12 is erected to the support position. The inner telescoping rods 92 and 115 may be returned into the associated outer telescoping rods by depressing the stop buttons 104 and 121 respectively for collapsing the collapsible backrest 12 to the hand portable packaged form shown in FIG. 1.

Another strap or locking belt 152 is fastened at one end, as by stitching 154 (FIG. 3), to the top of the membrane 134 at an angle such that the strap 152 projects outwardly from the fold 156 of the membrane 134 inherently formed as shown in FIG. 2 when the channel members 14 and 16 are adjacent each other and the upper part of the membrane 134 is folded downwardly as shown in FIG. 2. In this partially folded position, the bottom portion of the membrane 134 may also be folded upwardly and back on itself as shown in FIG. 2, whereupon the so folded membrane 134 may then be wrapped around the channels 14 and 16 and associated components until snap fastener members 158 and 160 on the strap 152 engage each other with the strap 152 extending about the wrap around membrane 134 to form a compact, readily hand portable packaged backrest 12 as shown in FIG. 1.

It will be noted that an extension 162 of the membrane 134 is provided to form a suitable ground cover pad on which the user may sit when occupying the erected collapsible backrest 12 as shown in FIG. 6. The ground cover extension 162 has the desirable further function and advantage, when occupied by the user, of providing an anchor for the backrest 12 from the weight of the

individual sitting thereon. The effect of this anchoring function is such that when the individual sitting on the extension 162 rests against the backrest area 114, the major portion of the resulting load will be directed through the channels 14 and 16 to the ground support pads 28 to the contact area 38 which is made of a sufficient ground contact area dimension to prevent sinking into the terrain 40.

It will also be noted that when the collapsible backrest 12 is in the erected support position shown in FIG. 6 the strap 152 is always well above the terrain 40, thereby remaining in a position where it will inherently tend to remain clean and free of dirt at the snap fastener components 158 and 160 to insure suitable condition for proper functioning.

Additionally it should be noted that tightening the strap 42 when the collapsible backrest 12 is in the erected support position shown in FIG. 6 helps to force the inner telescoping rods 92 and 115 away from each other and 20 against the outer edges of the upper elongated tubular formations 142 and 144 so as to maintain tensile loading on the top portion of the membrane 134, thereby providing a desirable firm, comfortable support for the user.

25 Also, it should be noted that when the backrest 12 is in the erected position shown in FIG. 6, the spacer bar sections 64 and 68 are distal from and well out of reach of the back support membrane 134, so that at no time is there any contact of rigid metal against any portion of the human body being supported on the membrane 134. All support to the user's back comes from the flexible membrane 134 itself, thereby insuring maximum comfort and relaxation to the user.

30 This invention is not limited to the particular details of construction and operation described, as equivalents will suggest themselves to those skilled in the art.

What is claimed is:

1. In a collapsible backrest, the combination of a pair 40 of channel members, each having two ends; an outer and inner telescoping rods in each of the channel members with the outer of each of the telescoping rods mounted to pivot at one end of the respective channel member and the telescoping rods of one channel member having no direct rigid connection with the telescoping rods of the other channel member; a flexible membrane carried by the telescoping rods to form the sole direct connection between said rods as well as the only support contact with the back of a user of said backrest; and a foldable cross bracing structure fixed to the channel members for 45 holding the channel members distal from each other in support position when unfolded and in substantial contact with each other when folded.

2. The combination as in claim 1 wherein the membrane includes a fold at each of its sides defining a tubular formation circumscribing the respective telescoping rods with provision for receiving the inner telescoping rod when extended axially of the outer telescoping rod, and releasable means in cooperative relation to the telescoping rods for holding the rods in extended position for 55 thereby increasing the support length of the collapsible backrest.

3. The combination as in claim 2 having additionally a flexible strap with one end fixed to the top of membrane and fastening means on the strap for holding the backrest in a compact bundle formation in the collapsed position.

4. The combination as in claim 1 wherein the cross bracing structure includes a spacer bar comprised of two 60 elongated sections fixed together at their extremities to pivot with respect to each other and each section mounted at its opposite extremity to pivot on the respective channel member, and an angularly disposed rigidizing member for each of the sections pivotally mounted on the respective section and the associated channel member for pro-

viding support to the spacer bar when the backrest is in the erected use position.

5. In a collapsible backrest, the combination of a pair of elongated rigid support members, a pair of rods coupled in manner to provide extensibility of one with respect to the other, a pair of said extensible rods for each of said elongated support members pivotally mounted to the associated support member, the telescoping rods associated with one of said support members having no direct rigid connection with the telescoping rods associated with the other support member, a flexible membrane having two sides fixed to the extensible rods to form the sole direct connection between said rods as well as the only support contact with the back of the user of said backrest, and a cross bracing structure fixed to the elongated support members and having capacity for folding and unfolding in scissor-like action for thereby selectively holding the elongated support members and extensible rods separated the full width of the membrane in support position and in substantial contact with each other in the collapsed position.

6. The combination as in claim 5 having additionally a ground support pad for each of the elongated support members pivotally mounted on the associated support member to swing into ground supporting relation to the elongated support member when in the erected support position.

7. In a collapsible backrest, the combination of a pair of channel members, each having two ends and a guide slot; an outer and inner telescoping rods in each of the channel members with the outer of each of the telescoping rods mounted to pivot at one end of the respective channel member; a flexible membrane carried by the telescoping rods; and a foldable cross bracing structure fixed to the channel members for holding the channel members distal from each other in support position when unfolded and in substantial contact with each other when folded, the cross bracing structure including a spacer bar comprised of two elongated sections fixed together at their extremities to pivot with respect to each other, each section being mounted at its opposite extremity to pivot on the respective channel member, an angularly disposed rigidizing member for each of the sections pivotally mounted on the respective section and having a follower slidably carried in said guide slot of the associated channel member, and means for locking said follower in fixed position in said guide slot for providing support to the spacer bar when the backrest is in said unfolded use position.

8. In a collapsible backrest, the combination of a pair of channel members, each having two ends; an outer and inner telescoping rods in each of the channel members with the outer of each of the telescoping rods mounted to pivot at one end of the respective channel member; a flexible membrane carried by the telescoping rods; and a foldable cross bracing structure fixed to the channel members for holding the channel members distal from each other in support position when unfolded and in substantial contact with each other when folded, the cross bracing structure including a spacer bar comprised of two elongated sections fixed together at their extremities to pivot with respect to each other, each section being mounted at its opposite extremity to pivot on the respective channel member, an angularly disposed rigidizing member for each of the sections pivotally mounted on the respective section and the associated channel member for providing support to the spacer bar when the

backrest is in said unfolded use position, and an elongated arm having two ends with one end mounted to pivot on one of the outer telescoping rods and the other end adapted for attachment to selected positions on the corresponding channel for providing a selective angle of support for the backrest.

9. In a collapsible backrest, the combination of a pair of channel members, each having two ends; an outer and inner telescoping rods in each of the channel members with the outer of each of the telescoping rods mounted to pivot at one end of the respective channel member; a flexible membrane carried by the telescoping rods; and a foldable cross bracing structure fixed to the channel members for holding the channel members distal from each other in support position when unfolded and in substantial contact with each other when folded, the cross bracing structure including a spacer bar comprised of two elongated sections fixed together at their extremities to pivot with respect to each other, each section being mounted at its opposite extremity to pivot on the respective channel member, an angularly disposed rigidizing member for each of the sections pivotally mounted on the respective section and the associated channel member for providing support to the spacer bar when the backrest is in said unfolded use position; and a flexible cord fixed to the channel members at positions distal from the spacer bar and in opposed relation to the ends mounting the telescoping rods, and of a length tending to fulcrum the channel members at the spacer bar to cause the extended inner telescoping rods to press outwardly against the membrane.

10. In a collapsible backrest, the combination of a pair of channel members, each having two ends; an outer and inner telescoping rods in each of the channel members with the outer of each of the telescoping rods mounted to pivot at one end of the respective channel member; a flexible membrane carried by the telescoping rods; and a foldable cross bracing structure fixed to the channel members for holding the channel members distal from each other in support position when unfolded and in substantial contact with each other when folded, the cross bracing structure including a spacer bar comprised of two elongated sections fixed together at their extremities to pivot with respect to each other, each section being mounted at its opposite extremity to pivot on the respective channel member, an angularly disposed rigidizing member for each of the sections pivotally mounted on the respective section and the associated channel member for providing support to the spacer bar when the backrest is in said unfolded use position; and a second channel member pivotally mounted to the other end of each of the first mentioned channel members with capacity to swing outwardly to provide area support on the terrain when the backrest is in the erected position and to swing into the first mentioned channel member for compacting into the collapsed package position.
